UNITED STATES PATENT OFFICE

141,216

DESIGN FOR A COMBINATION BABY WALKER AND STROLLER

Frank S. Nanna, North Lake Village, Ill.

Application March 14, 1945, Serial No. 118,484

Term of patent 14 years

(Cl. D14—14)

To all whom it may concern:

Be it known that I, Frank S. Nanna, a citizen of the United States, residing at North Lake Village (Melrose Park post office), in the county of Cook and State of Illinois, have invented a new, original, and ornamental Design for a Combination Baby Walker and Stroller, of which the following is a specification, reference being had to the accompanying drawings forming part thereof.

Fig. 1 is a perspective view of a combination baby walker and stroller showing my new design; Fig. 2 is a top plan view of the baby walker and stroller shown in Fig. 1 with the handle indicated in dotted lines broken away for convenience of illustration;

Fig. 3 is a side elevational view of the same which also has the handle shown in dotted lines broken away for convenience of illustration.

The dominant features of my design reside in the portions shown in full lines in the drawings.

I claim:

The ornamental design of a combination baby walker and stroller, substantially as shown and described.

FRANK S. NANNA.
